United States Patent Office

Des. 214,653
Patented July 8, 1969

214,653

HOUSING FOR A CAMERA

Donald M. Aubrey, Union, Ill., assignor to Aubrey Manufacturing Inc., Union, Ill., a corporation of Delaware

Filed Mar. 1, 1968, Ser. No. 10,799

Term of patent 14 years

Int. Cl. D16—01

U.S. Cl. D61—1

FIG. 1.

FIG. 2.

FIGURE 1 is a front, perspective view of the housing for a camera, showing my new design.

FIGURE 2 is a rear, perspective view of the housing for a camera.

The broken line showing of lens assembly in FIGURE 1 is for illustrative purposes only.

I claim:

The ornamental design for a housing for a camera, as shown and described.
